UNITED STATES PATENT OFFICE.

FRED E. NORTON, OF YOUNGSTOWN, OHIO.

AUTOMATIC REGULATOR FOR AIR AND GAS COMPRESSORS.

No. 852,976.

Specification of Letters Patent.

Patented May 7, 1907.

Application filed April 11, 1906. Serial No. 311,033.

To all whom it may concern:

Be it known that I, FRED E. NORTON, of Youngstown, Mahoning county, Ohio, have invented a new and useful Automatic Regulator for Air and Gas Compressors, of which the following is a full, clear, and exact description, reference being had to the accompanying drawings, forming part of this specification, in which—

- 10 Figure 1 is a side elevation of one form of compressor embodying my invention; Fig. 2 is a plan view of the same; Fig. 3 is a side view, partly broken away, showing a modified arrangement of the governor; Fig. 15 4 is a side view, partly in section showing the invention applied to a compressor having a different form of valves; and Fig. 5 is an end view of Fig. 4.

The object of this invention is to provide 20 means for the automatic regulation of air or gas compressors, whereby the quantity of air or gas delivered by the compressor may be varied so as to cause the compressor to deliver a small quantity of air or gas at a 25 high pressure, or a larger quantity at a lower pressure, or to deliver a variable quantity at a constant pressure. I accomplish this by means of certain novel mechanism whereby the inlet of air or gas to the compressor 30 cylinder is regulated by means of a governor, so that at maximum normal speed the compressor will deliver its full capacity of air, while at lower speeds the governor will reduce the quantity of air delivered and hence 35 the power required to operate the compressor.

My invention also consists in the novel construction, arrangement and combination of parts all substantially as hereinafter described and pointed out in the appended 40 claims.

Referring first to the form of compressor shown in Figs. 1, 2, and 3, of the drawing, in which the valves are of the circular or Corliss type, the numerals 2 designate the 45 inlet valves for the compressor cylinder 3. These valves are actuated by link connections 4 with the arms of a rocker 5, which is, in turn, actuated by an eccentric rod 6 from an eccentric 7 on the main shaft 8. 50 The action of this eccentric is controlled by a governor consisting of weights 9 mounted on arms 10 pivoted at 11 to fly-wheel 12. The centrifugal force of the weights 9 is resisted by means of springs 13, which are con-

nected at one end to the fly-wheel and at the 55 other end to the links 14 and 14^a which connect the arms 10 with the eccentric 7. The arms 10 and the links 14 are connected by links 15. The arrangement of these parts is such that as the weights 9 are moved by centrifugal force of rotation, the eccentric is rotated around the shaft 8. When the weights move outwardly, the direction of this rotation is in the same direction as that of the shaft 8, and when the weights move inwardly, the 60 eccentric is rotated in the opposite direction.

The governor arrangement shown in Fig. 3 is similar to that shown in Fig. 1, with the exception that instead of mounting the parts upon the fly-wheel, they are mounted upon a 70 governor wheel 16 on the shaft 8. Each of the inlet valves 2 is mounted in a valve chamber 17 having an inlet port 18 and cylinder admission port 19. Above each valve 2 is a second valve 20, mounted in the valve 75 chamber 21 which has an inlet port 22, a cylinder admission port 23 and an outlet port 24, the latter communicating with the discharge port 25 of the compressor through a third valve 26, which is also of the cylindrical type. The valves 20 are operated by a connection 27 with an eccentric 28 on the shaft 8, which has a fixed movement relatively to that of the compressor piston. The valves 26 are operated by pistons 29 80 working in cylinders 30, and connected with the respective valves through the piston rods 31, links 32 and arms 33. The cylinders 30 are connected at one side of the piston by a pipe 34 which communicates with the cylinder 90 3 and gives full cylinder pressure to that side of the piston 29. Each cylinder 30 is connected at the opposite side of the piston by pipe 35, which communicates with the discharge port 25 of the compressor. The 95 full area of each of the pistons 29 is thereby exposed to cylinder pressure at one side, while the annular area at the opposite side of the piston is exposed to discharge pressure, the comparatively small area of the 100 plunger being also exposed to atmospheric pressure. By reason of this arrangement, the valves 26 may be made to open before the pressure in the cylinder equals the pressure in the discharge port, thus securing a 105 prompt discharge of air from the cylinder. The inlet valves 2 control the admission of air to the cylinder through the ports 19.

The valves 20 operate as combined inlet and outlet valves, their motion having a definite relation to the piston motion in the way usual for compressors. These valves admit 5 air to the cylinder 3 through the ports 22 and 23 near the beginning of the forward or suction stroke of the piston, and close such ports at the end of said stroke. They also control the communication between the 10 cylinder and the exhaust port 24, the latter being positively open near the beginning of the compression stroke, and closed near the end of such stroke. While these valves positively open the communication between the 15 discharge ports 23 and 24, air or gas cannot, however, be discharged from the cylinder until the valves 26 are in position to connect the ports 24 and 24^a. The action of the inlet valve 2, as will be seen, is controlled by the 20 action of the governor. When the compressor is running at slow speed, the governor weights 9 are at their innermost positions, and the eccentric 7 is so set that at this time the inlet valve 2 leaves the port 19 open 25 for any desired part of the compression stroke of the piston, air being thus expelled through this port, and the port 18, without being compressed. As the speed of the compressor increases, the weights 9 move 30 outwardly, the eccentric 7 is advanced, and the port 19 is consequently closed earlier in the compression stroke of the piston, so that a larger quantity of air or gas is retained in the cylinder and is compressed.

35 In the form of compressor shown in Figs. 4 and 5, 36 designates the main inlet valves. Each of these valves is of cylindrical form and slides longitudinally on a barrel 37 so as to control the cylinder admission port 38. 40 These valves also control the communication between the cylinder and the exhaust chamber 39 in such a manner that this communication is open near the beginning of the compression stroke, and is closed at the end of 45 the compression stroke, while the port 38 is open near the beginning of the suction stroke and closed near the end of such stroke. The valves 36 are operated by connections 40 with an eccentric on the main shaft which 50 has a fixed travel relatively to the movement of the compressor piston, in the same manner as the eccentric 28 of the compressor first described. The valves 36, as will be seen, correspond in function to the valves 20 of the 55 compressor first described, being combined inlet and outlet valves having a definite movement relatively to the piston motion. The valves 36 positively open the communication with the exhaust chambers 39, but the 60 discharge of the air or gas into the delivery chamber 41 cannot take place until the opening of a supplementary valve 42, which controls the communication between the chambers or discharges 39 and 41. The valve 42 65 is shown as being a pot valve, corresponding

in function to the valves 26 of the compressor first described. This valve has a closing spring 43 and is preferably opened by means similar to that shown for operating the valves 26. Above the valve 36 is a ring valve 44, 70 which is arranged to slide on a barrel 45, and which controls the port 46 which connects the cylinder with the inlet chamber 47. The chamber 48 in the interior of the barrel 45 is always in communication with the cylinder, 75 and a pot valve 49 similar to the valve 42 is provided for controlling the communication between the chamber 48 and the discharge passage 41^a, said valve being always free to lift and discharge air from the cylinder in 80 case of excessive pressure. This valve has a closing spring 50. This spring is preferably somewhat stronger than the spring 43, so that normally the valve 42 will control the normal discharge, while the valve 49 will lift 85 any accidental overpressure occurs in the cylinder. The valve 44 is driven through a suitable connection with a governor, similar to that described for operating the valves 2 in the compressor first described, so that it 90 has a motion which varies in phase from the normal so as to remain open for a greater or less part of the compression stroke, as determined by the position of the governor. The operation of this form of the invention is substantially similar to that of the form first described.

It is not necessary that the governor controlled eccentric and governor therefor be mounted directly on the driving shaft 8 of the compressor as shown, nor that the arrangement of governor weights and springs be that shown in the drawings, since I may employ fly-wheel governors of any well known type. It is also obvious that various 105 forms of valves may be employed which will accomplish the same purpose as the forms herein described.

It is difficult, if not impossible, to control the main inlet valve so that its point of closing may be regulated, while the point of opening remains constant. It is essential to the quiet and perfect operation of a compressor that the opening of the inlet valve be just at the point when the air in the clearance has expanded to the inlet pressure. A variation from this condition leads to noisy and destructive action of the valves, since delayed opening means that a partial vacuum is formed in the cylinder causing noisy 110 action and lifting of the inlet valves, while an accelerated opening results in the air being blown out of the clearance violently and in noisy action of the outlet valves. To avoid this action, I provide that the main inlet valve has a positive mechanical motion in 115 definite and constant phase to the main compressor piston, while the regulation is by means of an auxiliary inlet valve controlled by a governor. As shown and described, it 120

130

is impossible for this auxiliary valve to have any effect on the opening event controlling the admission of air to the cylinder. The main valve will always control this event 5 since however much I delay the closing of the auxiliary valve, the opening will be similarly delayed, which has no effect on the compressor as regards time of action, since the main inlet valve will already be open. At 10 the extreme of delivery at full stroke, the auxiliary valve will open at the same, or substantially the same, time as the main inlet valve, while at the other extreme, the auxiliary inlet valve will close at the end of discharge stroke and remain closed during the 15 entire inlet stroke.

My invention is of peculiar advantage in compressors which are driven by gas engines, or other motive power, in which the turning 20 effort is mainly independent of the speed through a small range, since the governor weights and springs may be so proportioned as to rotate the eccentric through its full movement, while the speed change may be as 25 small or as large as the nature of the driving power demands. In starting up such a compressor the load is automatically removed, since the valve 2, or 44, will remain open during the whole or greater part of the compression 30 stroke of the piston. When normal speed is reached, however, the compressor will deliver the maximum volume of air.

The invention is also of great advantage in connection with blowing engines or blast furnaces which are operated with furnace gases. In such engines it has been necessary heretofore to provide for a great excess of power in the design of the engine, in order to drive the air pistons against high pressure with poor 40 gas. This is obviated by my invention, by reason of the self-adjustment of the blowing capacity to the quality of fuel supplied. It is also essential that engines used for this purpose shall not accidentally stop when exposed to sudden variations in pressure, and this is guarded against by the improved valve gear described, which permits the engine to run at nearly full speed against any desired pressure. It is also essential for blast 45 furnaces purposes to deliver very little air at times and at very low pressure. This may be accomplished by my improved compressors by simply adjusting the main governor so as to run the engine at near the lower limit 50 of the fly-wheel governor, which will cause the engine to run at nearly full speed but to deliver very little air.

What I claim is:—

1. In a compressor, the combination of a 60 combined inlet and outlet valve having a motion which is fixed relative to that of the piston, and an auxiliary inlet valve having an automatic variable motion controlled by a governor to thereby vary the capacity of the 65 compressor; substantially as described.

2. In a compressor, a combined inlet and outlet valve, an auxiliary inlet valve, and a speed governor for controlling the operation of the auxiliary valve; substantially as described.

3. A blowing engine having a main inlet valve, and an auxiliary inlet valve, and a speed governor controlled operating mechanism for said auxiliary valve; substantially as described.

4. In a compressor, the combination with a combined inlet and outlet valve having a fixed motion relative to the movement of the compressor piston, of an auxiliary automatic outlet valve, and a supplementary inlet valve having a variable movement controlled by a speed governor; substantially as described.

5. In a compressor, the combination with a combined inlet and outlet valve having a fixed motion relative to that of the compressor piston, of an auxiliary automatic outlet valve, and a supplementary inlet valve having a variable motion controlled by a speed governor, whereby its point of closing is controlled by said governor to thereby vary the amount of air caught and compressed in the cylinder, the main inlet valve having its movement so timed as to determine positively the time of admission during the inlet stroke and to open and close the discharge passage at or near the end of the stroke; substantially as described.

6. In a compressor, the combination with a combined inlet and outlet valve having a fixed motion relative to that of the compressor piston, of an auxiliary automatic valve arranged to control the opening of the cylinder discharge, and means whereby said valve may be opened before the cylinder pressure is sufficient to balance the pressure of the discharge; substantially as described.

7. In a compressor, the combination with a combined inlet and outlet valve, having a fixed motion relative to that of the compressor piston, an auxiliary outlet valve, means for operating the auxiliary valve controlled by the pressures in the compressor cylinder and discharge pipe, an auxiliary inlet valve, and a speed governor for controlling the operation of said inlet valve whereby said valve is closed at a varying point in the compression stroke of the piston; substantially as described.

8. In a compressor, a combined inlet and outlet valve, connections for operating said valve in definite time relation to the piston motion of the compressor, and an auxiliary inlet valve independent of the first named valve, and connected to the engine governor and controlled thereby, said valve being arranged to leave its inlet port open during any desired part of the compression stroke; substantially as described.

9. In a compressor, a main inlet valve, 130

4
connections for operating said valve in definite time relation to the piston stroke of the compressor, and a governor-controlled auxiliary inlet valve arranged to leave its inlet port open during any desired part of the compression stroke; substantially as described.

10. In a compressor, a combined main inlet and outlet valve, connections for operating the same in definite relation to the piston motion, an auxiliary outlet valve controlled by the pressure in the cylinder and arranged to open the discharge port before the pressure

in the cylinder equals the pressure in the discharge port, an auxiliary inlet valve, a governor, and actuating connections for the auxiliary inlet valve controlled by the governor; substantially as described. 15

In testimony whereof, I have hereunto set my hand.

FRED E. NORTON.
